UNITED STATES PATENT OFFICE.

ERICH THUERMEL, OF CHARLOTTENBURG, GERMANY, ASSIGNOR TO SIEMENS & HALSKE, A. G., OF BERLIN, GERMANY, A CORPORATION OF GERMANY.

PUPIN COIL.

1,184,047.

Specification of Letters Patent. Patented May 23, 1916.

Application filed May 22, 1913. Serial No. 769,185.

To all whom it may concern:

Be it known that I, ERICH THUERMEL, a citizen of the German Empire, and residing at Charlottenburg, Germany, have invented 5 certain new and useful Improvements in Pupin Coils, of which the following is a specification.

My invention relates to Pupin coils, and particularly to those used in telephonic and 10 telegraphic systems such as, for example, that shown in U. S. Patent to Ebeling 960,856.

It has been proposed to provide a four-wire telephone line for enabling three telephonic conversations to be carried on simultaneously or for telegraphing. This four-wire line consists of two pairs of two-wire lines, and may itself be used as a third line. In this case each of these two-wire lines 15 forms the single line of the third pair of lines. In such or similar systems, it has been proposed to employ a special arrangement of inductive coils and a suitable connection thereof and thereby effectively to 20 provide the whole system with Pupin coils. If coils having windings located one beside another are employed large resultant and stray fields are produced as soon as the 25 various windings have currents flowing through them in opposite directions. These resultant fields may cause cross conversation from the two-wire line to the four-wire line, and reversely. The stray fields produce eddy currents in the metallic protective caps 30 surrounding the coils and thereby cause losses of energy which, like interpolated resistances, exercise a damping action on the telephone currents.

The same phenomena occur, of course, also 40 when such coils are used in those Pupin lines over which telegraphic messages are simultaneously sent (simultaneous working). Here also the telegraph current passing through the two branches of the two-wire 45 line in the same direction produces in the coils fields of opposite direction which can only partially neutralize one another, so that disturbant noises produced by telegraphic current may possibly occur in the receiver.

Also, in the case of ordinary pupinized 50 aerial lines it is important to construct coils which are insensitive to a current passing in the same direction through the two branches of the two-wire line, such as may arise, for 55 example, owing to the influence of adjacent

single telegraph or high-tension lines, because otherwise disturbant noises transmitted from the adjacent line by induction may occur in the two-wire line.

A primary object of my invention is to diminish the stray fields of the coils and the disturbing resultant fields to such an extent that their action can be practically neglected. To this end, I divide those coils which are associated together in pairs into 60 portions, and I arrange the portions one surrounding another, the one coil being located in one or several layers or portions between the layers or portions of the other coil. According to my invention, in each 65 plane transverse to the axis of a coil the number of portions of one coil is different from the number of portions of the other coil. This plane transverse to the axis of a coil is hereinafter called the winding 70 plane. The portions of the coils which belong to one pair of coils are superposed in such manner that as uniform distribution as possible of the fields produced is obtained 75 over each winding plane. Whenever current flows in each pair of coils in such manner that the coils oppose one another magnetically, practically no resultant field can be produced in any of the said planes. Also, the windings have simultaneously 80 practically the same capacity relatively to 85 the core and protective cap.

Several embodiments of my invention are illustrated by way of example in the accompanying drawing, wherein:—

Figure 1 is a diagram of a Pupin coil constructed in well known manner; Figs. 2 and 3 are longitudinal and transverse sections, respectively, showing one form of the same, and Figs. 4 and 5 are like views, respectively, showing another known form of Pupin coil; Figs. 6 and 7 are like views, respectively, showing an improved Pupin coil according to my invention, and Fig. 8 is a diagram of connections relating thereto; 90 Figs. 9 and 10, Figs. 11 and 12 and Figs. 13 and 14 are longitudinal section and diagram, respectively, showing other forms of Pupin coils according to my invention.

Referring to Figs. 1 to 3, this coil is used for pupinizing the two lines of a four-wire line of the system described, and each of the two coils A, B is wound in one or more layers on the one or the other half of the core K. When a telephone current passes 95 100 105 110

along the two-wire line it flows through the coil A in the direction from *a* to *b* and through the coil B in the direction from *c* to *d*, as indicated by the arrows shown in full lines, so that the two coils produce like fields. As indicated by the dotted arrows, the current of the four-wire line flows through both coils in the same direction, for example from *a* to *b* and from *d* to *c*. The fields which now oppose one another do not however neutralize one another, but at the points *a*, *d* and *b*, *c* considerable leakage of the lines of force occurs toward the protective cap surrounding the coil, whereby the above-mentioned disadvantages are occasioned.

Figs. 4 and 5 show an arrangement of a Pupin coil in which the one coil A is wound over the other coil B. In this arrangement no poles can form, it is true, because both coils completely surround the core, but even now the fields produced cannot entirely neutralize one another. This is owing to the areas of section inclosed by the individual coils being unequal. It follows that if the two coils are to possess equal inductances the outside coil must have fewer turns than the inner. Under these circumstances the fields produced by the two coils cannot neutralize one another and a disturbing resultant field remains which produces an induced current which flows through the coils in series and the appertaining two-wire line like a talking current. Consequently, cross conversation from the four-wire line of the two-wire line can occur, and reversely.

Figs. 6 and 7 show a Pupin coil in which, according to the invention, the one of the two coils is divided into two portions A_1 , A_2 inclosing between them the other coil B. As the diagram of connections in Fig. 8 shows, the two portions A_1 , A_2 are connected in series in such manner that they produce a magnetization in the same sense; they possess approximately equal inductances and both together have the same total inductance as the coil B located between them.

Fig. 9 shows a Pupin coil in which the one coil is subdivided into three portions A_1 , A_2 , A_3 which inclose between them the other coil divided into two portions B_1 , B_2 . As Fig. 10 shows, the portions of each coil are connected in series and likewise in such manner that they produce fields of the like sense. In the form represented in Fig. 11 the individual coils are arranged with portions not only one over another, but also beside one another. On the one half of the core K the one half B' of the one coil is arranged between two portions A_1 , A_2 of the other coil, while on the other half of the core the former coil is divided into two portions B_1 , B_2 which surround the second half A' of the other coil. Fig. 12 shows the connection of the portions of the coils.

Figs. 13 and 14 show the arrangement of a Pupin coil specially suitable for pupinizing the four-wire line. The individual coils of this Pupin coil for each of the four lines are distributed on the four quadrants on a common core. For the one two-wire line L_1 consisting of the outgoing and return line the one portion B'_1 of the coil B connected in the return line is arranged on the one quarter of the core between the one half of the A-coil in the outgoing line divided into two portions A_1 , A_2 , while on the diametrically opposite quarter the other halves B' and A'_1 , A'_2 of these coils are wound in exactly similar manner. The coils in the second two-wire line L_2 may be arranged in an analogous manner on the two other quarters of the cores diametrically opposite one another. Fig. 13 shows, however, another possibility of winding for these coils, corresponding to the arrangement according to Fig. 11. Namely, on the one quarter of the core are arranged the portions C_1 , C_2 of a coil connected in the outgoing line; these portions surround the half D' of the coil connected in the return line, while on the other quarter of the core is mounted the remainder C' of the former coil between the parts D_1 , D_2 of the coil connected in the return line. A corresponding exchange of the portions of the coils can of course be made with regard to the coils A and B. As the diagram of connections in Fig. 14 shows, the individual portions of a coil are connected in series and the coil in the one wire of a two-wire line produces a magnetization in a sense opposite to that of the coil connected in the other wire.

The forms shown in Figs. 6 to 14 are only examples of Pupin coils having iron cores according to the invention, which however can be varied in various ways. The various arrangements of coils can also be advantageously employed for Pupin coils without iron cores.

I claim:

1. A Pupin coil for telephone lines and the like comprising in combination a pair of coils wound in portions one surrounding another, the number of portions of one coil in any winding plane being one more than the number of portions of the other coil in the same winding plane, and the portions of one coil alternating with the portions of the other coil.

2. A Pupin coil for telephone lines and the like comprising in combination a pair of coils wound in three portions one surrounding another, the number of portions of one coil in any winding plane being one more than the number of portions of the other coil in the same winding plane, and the two portions of one coil inclosing the other coil.

3. A Pupin coil for telephone lines and the like comprising in combination a core

and a pair of coils belonging to different lines and wound on said core in portions one surrounding another, the portions of one coil alternating with those of the other coil, 5 and the number of portions of one coil in any winding plane being one more than the number of portions of the other coil in the same winding plane.

4. A Pupin coil for telephone lines and 10 the like comprising in combination a core and a pair of coils belonging to different lines and wound on said core in portions one surrounding another, one or more of the portions of each coil being wound on the one 15 half of the core and the remainder on the

other half, the number of portions of one coil in any winding plane being one more than the number of portions of the other coil in the same winding plane, and the one or more portions of one coil in any winding 20 plane alternating with the one or more portions of the other coil in the same winding plane.

In testimony whereof I have signed my name to this specification in the presence of 25 two witnesses.

ERICH THUERMEL.
